UNITED STATES PATENT OFFICE.

GROVER C. LOENING, OF NEW YORK, N. Y.

AIRPLANE.

1,394,630.

Specification of Letters Patent. Patented Oct. 25, 1921.

Application filed May 13, 1919. Serial No. 296,802.

To all whom it may concern:

Be it known that I, GROVER C. LOENING, a citizen of the United States, and resident of the borough of Manhattan, in the city, 5 county, and State of New York, have invented a new and useful Airplane, of which the following is a specification.

The invention relates to airplanes, and particularly to seaplanes or flying boats, 10 though some of its features are applicable also to land planes. It embraces a novel construction and organization including numerous new parts and combinations, whereby manufacture is facilitated and cost is reduced and general improvement in the machines is effected. A leading object is simplicity, with consequent possible economy of production, decrease in weight, increase in speed, decrease in horsepower required, decrease in fuel consumption, etc., in conjunction 15 with a high degree of strength and stability. Another important object is to provide a construction of flying boat which combines safety for the occupants with unobstructed vision and ease of control. Another object is to relieve the wings of the weight of the side pontoons in flight and of stresses transmitted through them when on the water. Still another object is to eliminate the complication and head resistance of 20 ordinary bracing and staying, and to provide a simple and advantageous form of bracing which contributes materially to the lift. A further object is to provide the flying boat with a launching carriage, from which the machine cannot be prematurely separated, and which is cast off by the pilot. It is also an object to enable the planes to be cast off in case of emergency when the 25 machine is upon the water. Other objects and features will be come apparent to those skilled in the art.

In the accompanying drawings:

Figure 1 is a sectional side elevation of the 45 preferred embodiment of the invention;

Fig. 2 is a plan view thereof;

Fig. 3 is a front elevation;

Fig. 4 is an enlarged fragmentary cross-section;

Fig. 5 is an enlarged sectional elevation 50 on the line 5—5 of Fig. 4;

Fig. 6 is a cross-section through one of the struts; and

Fig. 7 is a sectional side elevation of another embodiment.

The body of the machine comprises a hull 1, which may be constructed with laminated

walls in accordance with existing practice. Instead of the usual multiplicity of fittings for carrying the overhead engine 2 and wings 3, I provide a unit hull and superstructure by extending the forward middle portions of the side walls upward to the requisite height. These extensions are designated 4, and as seen in Fig. 3 they constitute straight continuations of the lines of the sides converging inwardly and upwardly from the bottom of the hull. 60

In the preferred embodiment of the invention the forward part 5 of the hull is low 70 and decked over, and the front edges of the superstructure members 4 are upwardly and forwardly inclined, so that the top of the superstructure overhangs the part 5. The extensions 4 are desirably formed with large 75 side openings 8, but their forward portions 7 present flat, solid areas of substantial extent for a purpose which will appear. In rear of the front part 5 of the hull is the seat 8 for the pilot, with controls (not 80 shown), and in rear of that, below the back of the wings, is the observer's seat 9. The pilot's seat is between the side extensions 4, where he has a direct view forward between the extensions, sidewise and downward 85 through the openings 6, and upward through the open top of the superstructure, in rear of the engine bed 10 about to be described.

The tops of the converging side extensions 4 are united by simple cross-fittings 11, 12, 90 13, shown as channeled bars with sockets 14 toward their ends embracing the edges of the extensions, to which they are bolted. The fittings 11, 12, together with longitudinal bearer bars, 15 held in the closed-top 95 sockets 14 upon the tops of the wall extensions 4, of which they may be regarded as removable sections, constitute the engine bed. In this case the engine bed and the engine bolted thereto are forwardly located, in 100 advance of the seats 8, 9 and at the front of the wings, above which the engine rises. The propeller 16 on the front end of the engine shaft operates over the part 5 of the hull, which is low enough to afford it clearance, and in front of the solid parts 7 of the side wall extensions 4. The latter, being substantially straight in the longitudinal direction, act as fin areas upon the spiral current of air, thereby tending to neutralize the 105 torque of the propeller. 110

Behind the engine, supported in the top of the superstructure, between the wings, is the fuel tank 17 and above it the radiator 18.

Behind the gasoline tank, above the pilot's head, is the opening 19 for upward view, heretofore referred to.

The projecting ends of the top cross-fittings 12, 13 form sockets 20 for the reception of the inner ends of the spars 21 of the monoplane wings 3, the spars being held in said sockets by pins 22. The wings are thus attached to the superstructure at the sides of 10 the engine bed, and connected by the same, or in part by the same, cross-fittings which connect the engine-bearers.

The ends of the cross-fittings 12 and 13 also receive the inner ends of two pairs of 15 struts 23, which extend diagonally downward and outward beneath the forward and rearward parts of each wing. Similar parts of struts 24 extend outward and upward from the lower side portions of the hull, at 20 substantially less inclination to the horizontal than the struts 23, the outer ends of the struts 23 and 24 being united by fittings 25 to form V-brackets, the bases of which are secured to the remote upper and lower portions 25 of the body by the pins 26 and 27. At the extremities of these brackets, upon the fittings 25 or upon extensions of the struts, are mounted the side pontoons 28, which unite the bracing longitudinally at 30 each side of the machine. Additional pairs of struts 29 extend diagonally outward and upward and inward and downward between the apex fittings 25 and attachments 30 under the outer portions of the wing spars. 35 The wings are thus braced primarily to the lower part of the hull, and in lesser degree to the superstructure, by a deep cantaliver truss, of which the height of the body at the side extensions 4 substantially measures 40 the base. The side pontoons are carried by this bracing, and particularly by the brackets 23, 24, substantially independent of the wings, that is to say the wings neither sustain the weight of the pontoons in flight nor 45 receive thrust therefrom when riding upon the water. All of the braces act in both compression and tension.

The struts are of broad, wing-like cross-section, as shown in Fig. 6 and are set with 50 an angle of incidence; and, all of them having a horizontal projection, lift is derived from the entire bracing, which thus affords additional wing area. In the present instance the areas of the horizontal projections of the struts may be about one-sixth 55 of the wings.

The pins 22 connecting the inner ends of the wings to the superstructure, and the similar pins connecting the lower, inner 60 ends of the wing struts 29 to the fittings 25, are of quick-detachable character, so that in case of necessity the wings can be cast adrift, leaving the hull floating upon the water steadied by its out-riggers.

65 At the rear end of the hull, the side walls

are extended integrally upward to form fins 32, to which are attached the stabilizer 33, elevator 34, and twin rudders 35.

The hull is provided with an attached launching carriage and means for casting it off. This is accomplished in a simple manner by seating a bent axle 36 in a groove 37 across the bottom of the forward mid portion of the hull, where it is held by cables or other suitable connections 38 passing to 75 points of support within. By means of a trigger 39 accessible to the pilot the connections can be released and the axle and launching wheels 40 dropped off. In this way the boat cannot become displaced from 80 its carriage before it has been successfully launched, as has heretofore occurred with disastrous results.

Fig. 7 illustrates a pusher modification of the invention. Similar parts are designated 85 by the same reference numerals as in the other views, with super-character "a". The side extensions 4^a lack the forward fin projections 7 of the other form, and at the top it is sufficient to connect them by two cross-fittings (not shown). The engine bed is formed substantially as before, but upon the rear portion of the superstructure. The engine 2^a is reversed, and the propeller 16^a is at the back of the wings. The forward 95 part of the hull is constructed as a double cock-pit with seats 8^a and 9^a for pilot and observer substantially in the usual locations. The fuel tank 17^a is located between the side extensions 4^a, back of the pilot's seat. 100

What I claim as new is:

1. A seaplane having, in combination, a hull-body and superstructure, monoplane wings attached at the top of the superstructure, brackets comprising members united 105 to the upper part of the superstructure and to the hull, respectively, and extending outward and united at points beneath the wings, pontoons carried by said brackets, and members bracing the wings from said brackets. 110

2. A seaplane having, in combination, a hull-body and superstructure, monoplane wings attached at the top of the superstructure, brackets comprising members united to the upper part of the superstructure and to the hull, respectively, and extending outward and united at points beneath the wings, 115 pontoons carried by said brackets, and members bracing the wings from said brackets, said several members acting in both tension and compression and being of lift section.

3. A seaplane having a hull-body provided with integral upward extensions of its sides forming a superstructure, an engine bed arranged on the top of said superstructure, monoplane wings attached at the top of the superstructure, V-brackets comprising members united to the upper part of the superstructure and to the hull, respectively, and extending outward and united at points 120

125

130

beneath the wings, pontoons carried by said brackets, and members bracing the wings from said brackets.

4. A seaplane having, in combination, a hull-body and superstructure, monoplane wings attached at the top of the superstructure, brackets comprising members united to the upper part of the superstructure and to the hull, respectively, and extending outward and united at points beneath the wings, pontoons carried by said brackets, and members bracing the wings from said brackets, said brackets and members being in pairs at each side, spaced fore and aft, with the pontoons connected to both the forward and rearward brackets.

5. In a seaplane, the combination of a unit hull and superstructure, the latter formed by integral upward extensions of the sides 20 of the hull, an engine bed on the top of the superstructure, and a pair of monoplane wings joined with the top of the superstructure at the sides of the engine-bed.

6. A seaplane having a unit hull and 25 superstructure, the latter formed by integral upward extensions of the sides of the hull, an engine-bed on the top of the superstructure, monoplane wings joined at the sides of the engine-bed, and inclined struts acting 30 in both tension and compression connecting the outboard portions of the wings with the lower portion of the hull.

7. In a seaplane, a hull having integral 35 upward extensions of its side walls, and cross-fittings connecting said extensions at the top to form an engine-bed.

8. In a seaplane, a hull having upward extensions of its sides, cross-fittings connecting said extensions at the top, and wings attached to said fittings.

9. A seaplane having a hull with upward extensions of its sides, and cross-fittings between the tops of said extensions forming part of an engine-bed and affording wing 45 attachments.

10. In a seaplane, the combination of a hull having upward extensions of its sides, and a cross-fitting between said extensions at the top, said cross-fitting forming part 50 of an engine-bed and also having wing attachments.

11. In a seaplane, the combination of a hull having integral upward extensions of its side walls with engine bearers upon the 55 tops of said sides, and cross-fittings connecting said bearers.

12. In a seaplane, the combination of a hull having upward extensions of its sides with engine bearers upon the tops of said 60 sides, a cross-fitting connecting said bearers, and wing attachments on the ends of the fitting.

13. In a seaplane, the combination of a

hull having upward extensions of its sides, engine bearers on the tops of said extensions, 65 wings adjacent the engine bearers, and cross-fittings, said cross-fittings being common, in part at least, to the engine bearers and wings, connecting both.

14. In a seaplane, the combination with a 70 hull body and wings, of side pontoons, brackets supporting said pontoons from the body independent of the wings, struts supporting the wings from the pontoon brackets, and quick-detachable connections whereby 75 the wings can be cast off from the body and pontoons leaving the latter united upon the water.

15. A seaplane having a hull with a notch 80 in the bottom, a launching carriage comprising an axle seated in said notch, and means in the plane for holding the axle in the notch and for releasing the same when desired.

16. A flying boat, comprising a hull, integral upward extensions of the side walls 85 of the hull forming a superstructure, monoplane wings attached to said superstructure, diagonal strut bracing between the wings and hull, a forwardly located overhead engine 90 on the superstructure, and a propeller in front of the wings.

17. In a flying boat, the combination of a 95 hull, a superstructure comprising upwardly projecting and forwardly overhanging extensions of the sides of the hull, a forwardly located engine bed on the tops of said extensions, an engine and forward propeller driven thereby, and wings attached to the superstructure.

18. In a flying boat, the combination of a 100 hull, a superstructure comprising upwardly projecting and forwardly overhanging extensions of the sides of the hull, a forwardly located engine bed on the tops of said extensions, an engine and forward propeller driven thereby, and monoplane wings attached to the superstructure at opposite sides of the engine bed.

19. A flying boat, comprising a hull, a superstructure comprising upward extensions of the sides of the hull presenting flat forward fin areas, wings attached to the superstructure, a forwardly located engine bed thereon, an engine, and a propeller in 110 front of said wings and fin areas.

20. A flying-boat, comprising, in combination, a hull having converging sides, extensions of the sides walls of the hull continued straight upward in the converging relation 115 of the sides and joined at the top, an engine bed constructed on the superstructure thus formed, and wings attached to the superstructure directly at opposite sides of the engine bed.

GROVER C. LOENING.
